(57) **CLAIM**

The ornamental design for a can opening tab, as shown and described.

DESCRIPTION

FIG. 1 is an isometric view of the can opening tab.
FIG. 2 is a top plan view of the can opening tab of FIG. 1.
FIG. 3 is a bottom plan view of the can opening tab of FIG. 1.
FIG. 4 is a right end view of the can opening tab of FIG. 1.
FIG. 5 is a left end view of the can opening tab of FIG. 1; and,
FIG. 6 is a side view of the can opening tab of FIG. 1, the sides
are identical.

1 Claim, 3 Drawing Sheets---
